FIG. 2

UNITED STATES PATENT OFFICE

2,053,866

CAM GRINDING APPARATUS

Carl G. Flygare, Worcester, Mass., assignor to
 Norton Company, Worcester, Mass., a corpora-
 tion of Massachusetts

Application July 23, 1935, Serial No. 32,704

11 Claims. (Cl. 51—101)

This invention relates to grinding machines, and more particularly to a readily removable master camshaft assembly for a cam grinding machine.

Heretofore, it has been common practice to 5 grind a camshaft having a plurality of cams formed integrally therewith by mounting the camshaft to be ground on a rock bar which is rocked toward and from the periphery of a grinding wheel by means of a plurality of master cams 10 and a cooperating master cam roller to cause the camshaft to rock so as to produce a predetermined contour on the cam blank being ground. In the previous constructions, the rock bar has been formed with integral heads to form a support 15 for the rotatable master camshaft. Such a construction is suited only for grinding a single camshaft where the entire productive time of the machine may be used for grinding a large number of the same camshafts. In previous cam 20 grinding machines, it has been necessary to make substantial alterations in the machine in order to set up the machine for grinding a different camshaft.

In some automobile factories where various 25 sizes of gasoline motors are manufactured for automobiles and the like, there is not a sufficient quantity of camshafts to be ground to keep an individual cam grinding machine busy in grinding a single type of camshaft. It is, therefore, 30 desirable to provide a cam grinding machine which may be readily set up for grinding a cam- 35 shaft and in which the set-up may be readily changed for grinding a second and different cam- shaft so that the loss of time in changing over from one set-up to the other is reduced to a minimum.

It is one object of this invention to provide a 40 camshaft grinding machine which may be readily set up for grinding different camshafts.

It is another object of this invention to provide a camshaft grinding machine in which the 45 master cams may be readily interchanged.

It is still another object of this invention to 50 provide a camshaft grinding apparatus in which the master camshaft and master cams may be inserted or removed therefrom.

It is a further object of this invention to provide an integral master cam assembly which may 55 be readily located in operating position and readily removed therefrom and interchanged for another similar master cam assembly.

It is a further object of this invention to provide a cam grinding apparatus with a unitary readily 60 removable master cam assembly which may be

readily located in a predetermined position on a camshaft supporting rock bar. Other objects will be apparent from the following disclosure.

One embodiment of this invention has been 5 illustrated in the drawings, in which like reference numerals indicate like parts:

Fig. 1 is a fragmentary perspective view of a cam grinding machine embodying this invention;

Fig. 2 is a fragmentary end elevation of a cam- 10 shaft grinding apparatus embodying this invention, and

Fig. 3 is a fragmentary longitudinal rear eleva- 15 tion, on a reduced scale, of the rock bar and master cam assembly.

This invention consists broadly in providing a camshaft grinding machine in which the machine 20 may be readily set up for grinding different cam- shafts. The machine is so arranged that the master camshaft and set of master cams may be readily interchanged. The master cams are ro- 25 tatably supported on a unitary readily inter- changeable master cam assembly which may be located and clamped in a predetermined operat- 30 ing position on the machine.

A cam grinding machine has been illustrated in 35 the drawings including a base 10 which supports 25 a longitudinally movable work table 11 on a flat way 12 and a V-way 13. A grinding wheel 14 is rotatably supported on a transversely movable wheel slide 15. The slide 15 is provided with a depending nut 16 meshing with a feed screw 17 30 which serves to cause a transverse movement of the grinding wheel 14 relative to the table 11. The wheel feeding mechanism is not considered 35 a part of the present invention and consequently has not been illustrated in detail. This mecha- nism may be of any of the standard well-known 40 grinding wheel feeding mechanisms, such as, for example, that shown in the prior patent to Trefethen et al. No. 1,783,755 dated December 2, 1930, to which reference may be had for a de- 45 tailed disclosure of the wheel feeding mechanism.

A rock bar 20 is pivotally supported on table 11 by means of bearing brackets 21 and 22. The 45 rock bar 20 is arranged to be rocked relative to the periphery of the grinding wheel by means of a plurality of master cams 23 cooperating with a master cam follower roller 24 which is rotatably supported by brackets 25 on a rotatable 50 shaft 26. The master cam follower roller 24 may be shifted longitudinally to position it into operative relation with the plurality of master cams 23, either manually or by means of a suitable index mechanism, such as that shown in the 55

prior patent to Trefethen, et al. above referred to. An indexing mechanism of the Trefethen type has been illustrated comprising a yoke 30 which is fixedly mounted to the end of a rack 5 bar 31. The yoke 30 straddles the roller 24 and is arranged to move the roller 24 axially when the rack bar 31 is moved longitudinally. The rack bar 31 is moved longitudinally by means of a gear 32 which is mounted on a shaft 33 carried 10 by a gear 34 meshing with a gear 35. Gear 35 meshes with a gear 36 rotatably mounted on a stud 37. The gear 36 is connected and arranged to rotate with a star wheel 38. The star wheel 38 is arranged to be engaged by dogs 39 mounted 15 on a dog bar 40 which is fixedly supported on the base of the machine by means of a bracket 41. For further details of such an indexing mechanism, reference may be had to the prior patent to Trefethen. It is readily apparent from the 20 disclosure that when the work table 11 is moved longitudinally, the star wheel 38 engaging dogs 39 on dog bar 40 causes a rotation of star wheel 38 and through the gear 36, the gear 35, the gear 34, the gear 32, rack 31 and yoke 30 causes a 25 longitudinal indexing of the master cam roller 24.

The rock bar 20 is arranged to be rocked to and from an operating position by means of a fluid pressure mechanism including a cylinder 50 and a piston (not shown) which is connected by 30 a piston rod 51, through a pin 52, to a bracket 53 fixed on the rock bar 20. This mechanism is not considered a part of the present invention so that the details have not been shown. For a detailed disclosure, reference may be had to the 35 above-mentioned prior patent to Trefethen.

In order to attain the main object of this invention, a suitable readily removable master cam assembly is provided which enables setting up of the machines for grinding various cam-shafts without an unnecessary loss of time during the set-up. As illustrated in the drawings, such a master cam assembly may comprise a frame 60 having integral bearing members 61 and 62 which serve to rotatably support a master camshaft 63. The frame 60 is arranged to be 40 readily mounted on the rock bar 20 and readily removed therefrom. The rock bar 20 is preferably provided with a slideway, such as a dovetailed way 65 which mates with a corresponding 45 ly shaped dovetailed way 66 formed on the under surface of the frame 60. The dovetailed slide 65 only extends along a left-hand end portion (Fig. 1) of the rock bar 20 so that the master cam assembly carried by frame 60 may be readily removed from the rock bar by sliding it in an end-wise direction toward the right, as viewed in 50 Fig. 1.

The frame 60 may be clamped in a predetermined operating position on the rock bar 20 by 55 means of a clamping bar or gib 70, the lower part 71 of which mates with and engages a portion 72 of the dovetailed slideway 65 and the upper part 73 of which engages the notch 74 on the frame 60. The gib 70 is clamped in position by means of a 60 plurality of clamping screws 75 which pass through holes 76 in the clamping bar or gib 70 and are screw threaded into the frame 60. A nut 77 is mounted on each screw 75 and serves to clamp the gib 70 so as to lock the master cam assembly frame 60 in a predetermined operating 65 position on the bar 20.

It is desirable to provide a suitable locating means so that the frame 60 or successive frames corresponding to frame 60 may be located in a predetermined position on the rock bar 20. The 70 75

master cam assembly frame 60 is preferably provided with a locating lug 80 which is arranged to abut against a stop pin 81 fixedly mounted on the rock bar 20.

A camshaft 85 to be ground is mounted in the 5 usual manner and is rotatably supported on a center 86 on the left-hand end of master cam-shaft 63 (Fig. 3) and has its other end supported on a footstock center 87 which is mounted on an adjustable footstock 88. The footstock 88 is provided with a dovetailed slideway 89 which mates with a slideway 90 formed on the rock bar 20 so that the footstock may be adjusted longitudinally relative to the rock bar 20 to accommodate various lengths of camshafts. The camshaft 85, 15 to be ground, is rotated in unison with the master camshaft 63 by means of a driving pin 92 supported on a driving head 91 which is carried by the master camshaft 63.

A tapered portion 95 is provided on the right-hand end of the master cam spindle 63 (Fig. 3) and is arranged to be detachably connected to a flexible driving coupling in the manner shown in the above-mentioned prior patent to Trefethen.

In order to change the master cam assembly in 20 setting up the machine for grinding a different shaft, the operator first disconnects the driving coupling from the end 95 of the master camshaft 63 and then loosens the clamping nuts 71 on frame 60 and slides the master cam assembly 30 frame 60 carrying the entire assembly of master cams longitudinally relative to the rock bar 20 to disengage the slideway 66 from the slide 65 and thereby removes the entire assembly from the machine. A similar master cam assembly frame 35 60 with another set of master cams 23 shaped and timed for a different camshaft to be ground may then be readily slid into place on slideway 65, clamped thereon, and the tapered driving end 95 locked in driving relation with the master 40 camshaft rotating mechanism.

It will be readily apparent from the foregoing disclosure that a unitary master camshaft assembly is provided which may be readily located on or removed from an operating position on the 45 rock bar 20 and may be replaced with a similar unitary assembly for grinding a different cam-shaft without the necessity of rebuilding or re-fitting the various parts of the machine.

The operation of this mechanism is readily 50 apparent from the foregoing disclosure. The desired master camshaft assembly for grinding the particular camshaft to be ground is picked out and the frame 60 is slid into operating position with the slideway 66 engaging the mating slide 55 65 on rock bar 20 and moved toward the right, as viewed in Fig. 3, until the lug 80 engages stop pin 81. The slide 60 is locked in an operating position by means of the clamping nuts 71.

Having thus described my invention, what I 60 claim as new and desire to secure by Letters Patent is:

1. A cam grinding machine of the kind described, a longitudinally movable work table, a transversely movable grinding wheel slide, a rotatable grinding wheel on said slide, a rock bar pivotally mounted on said table, a rotatable cam-shaft support on said bar, a master cam roller rotatably and slidably supported on said table, and an interchangeable master cam assembly comprising a frame arranged to be attached in a predetermined position on said rock bar, a rotatable master camshaft on said frame having a plurality of master cams thereon, and means 75

including a clamping and locating device to removably secure the frame on said bar.

2. A cam grinding machine of the kind described, a longitudinally movable work table, a transversely movable wheel slide, a rotatable grinding wheel on said slide, a rock bar pivotally mounted on said table, a master cam follower roller rotatably and slidably mounted on said table, a footstock including a center adjustably mounted on said bar to support one end of a camshaft to be ground, and an interchangeable master cam assembly comprising a frame, a master camshaft rotatably supported on said frame having a plurality of master cams thereon and means to removably secure said frame in a predetermined position on said bar.

3. A cam grinding machine of the kind described, a longitudinally movable work table, a transversely movable grinding wheel slide, a rotatable grinding wheel on said slide, a rock bar pivotally mounted on said table, a rotatable camshaft support on said bar, a master cam roller rotatably and slidably supported on said table, a slideway formed on said bar, and an interchangeable master cam assembly comprising a frame, a rotatable master camshaft on said frame having a plurality of master cams thereon arranged to cooperate with said master cam roller to rock said bar to produce a predetermined contour on the cams being ground, and ways on said frame mating with the slideway on said bar to locate the frame in a predetermined position on the rock bar.

4. A cam grinding machine of the kind described, a longitudinally movable work table, a transversely movable wheel slide, a rotatable grinding wheel on said slide, a rock bar pivotally mounted on said table, a master cam follower roller rotatably and slidably mounted on said table, a footstock including a center adjustably mounted on said bar to support one end of a camshaft to be ground, and an interchangeable master cam assembly comprising a frame, a master cam rotatably supported on said frame having a plurality of master cams thereon, means to removably secure said frame in a predetermined position on said bar, and a camshaft supporting head on said spindle arranged to support the other end of a camshaft and rotate the same in unison with said master camshaft.

5. A cam grinding machine of the kind described, a longitudinally movable work table, a transversely movable wheel slide, a rotatable grinding wheel on said slide, a rock bar pivotally mounted on said table, a master cam follower roller rotatably and slidably mounted on said table, a footstock including a center adjustably mounted on said bar to support one end of the camshaft to be ground, and an interchangeable master cam assembly comprising a frame, a master camshaft rotatably supported on said frame having a plurality of master cams thereon, and a clamping device arranged to removably secure the frame in a predetermined position on said bar.

6. A cam grinding machine of the kind described, a longitudinally movable work table, a transversely movable wheel slide, a rotatable grinding wheel on said slide, a rock bar pivotally mounted on said table, a master cam follower roller rotatably and slidably mounted on said

table, a footstock including a center adjustably mounted on said bar to support one end of the camshaft to be ground, a slideway on said bar and an interchangeable master cam assembly comprising a frame, a master camshaft rotatably supported on said frame having a plurality of master cams thereon, ways on said frame mating with said slideway, and a clamping means to removably secure the frame in a predetermined position on said bar.

7. A cam grinding machine of the kind described, a longitudinally movable work table, a transversely movable wheel slide, a rotatable grinding wheel on said slide, a rock bar pivotally mounted on said table, a master cam follower roller rotatably and slidably mounted on said table, a footstock including a center adjustably mounted on said bar to support one end of the camshaft to be ground, a slideway on said bar and an interchangeable master cam assembly comprising a frame, a master camshaft rotatably supported on said frame having a plurality of master cams thereon, ways on said frame mating with said slideway, means to locate said frame in a predetermined position on said bar, a clamping means to removably secure the frame in said predetermined position.

8. A cam grinding apparatus of the kind described, a pivotally mounted rock bar, a rotatable camshaft support on said bar, a rotatable master cam follower roller, and an interchangeable master cam assembly comprising a frame, a rotatable master camshaft on said frame having a plurality of master cams thereon, means to align said frame on the bar, and clamping means to removably locate said frame in a predetermined operating position on said bar.

9. A cam grinding apparatus of the kind described, a pivotally mounted rock bar, a rotatable camshaft support on said bar, a rotatable master cam follower, a slideway on said rock bar, and an interchangeable master cam assembly comprising a frame, a master camshaft rotatably mounted on said frame having a plurality of master cams thereon, and a slideway on said frame mating with said slideway on the bar to removably locate the frame in a predetermined position.

10. A cam grinding apparatus of the kind described, a pivotally mounted rock bar, a rotatable camshaft support on said bar, a rotatable master cam follower, a slideway on said rock bar, and an interchangeable master cam assembly comprising a frame, a master camshaft rotatably mounted on said frame having a plurality of cams thereon, a slideway on said frame mating with the slideway on said bar, and means on said bar to locate the frame in a predetermined position.

11. A cam grinding apparatus of the kind described, a pivotally mounted rock bar, a rotatable camshaft support on said bar, a rotatable master cam follower, a slideway on said rock bar, and an interchangeable master cam assembly comprising a frame, a master camshaft rotatably mounted on said frame having a plurality of cams thereon, a slideway on said frame mating with the slideway on said bar, means on said bar to locate the frame in a predetermined position, and means to clamp the frame in said predetermined position on the bar.
